Walter Bryant
Letter Patent

The Schedule referred to in these Letters Patent and making part of the same containing a description in the words of the said Walter Bryant himself of his improvement denominated the anthracite heating stove

1. The external shell or frame of the stove is of cast iron of convenient dimensions for different families or establishments. 2. A common grate suitable for anthracite coal is fixed in front the bars bending inward & extending back to about the middle of the stove with a shelf underneath to receive the cinders which are deposited & removed when necessary in the usual manner. 3. In the rear of this grate is placed another grate consisting of perpendicular bars forming the rear wall of the furnace & a damper of cast iron is placed immediately behind this perpendicular grate governed by an exterior crank or handle. This damper is kept closed when the oven is not used & regulates the heat of the furnace from passing off to the rear. 4. The oven is placed in the rear of the stove. its bottom on a level with the top of the perpendicular grate. The heat from the furnace is communicated to its bottom by removing the damper before described & also passes freely from the furnace over the top but it may be increased or diminished as required by means of another damper placed on a level with the top of the oven & made to slide horizontally by means of exterior handles so as to close the whole or any part of the passage in the rear of the oven at pleasure. 5. The smaller boilers are placed forward immediately over the furnace & a larger one for washing &c in the rear over the oven. Near the center of the stove is fixed a perpendicular tube or pipe the top of which rises considerably above the top of the stove & the bottom of which opens by an aperture immediately under the main grate or furnace. The covers of the boilers are furnished with short pipes which receive the steam & convey it to the perpendicular tube where they are made by suitable apertures when need which apertures may at other times be closed by slides. The steam is admitted in common down these pipes & passes over

in the furnace when the effluvia are decomposed or neutralized by the heat. 6. The main grate or furnace may be enclosed at the sides & also in the rear above the firebox section or rear grate by a partition or lining of such stone or of any material suitable to resist the heat in such a situation. The heat may be increased by the application of a blower & the front of the furnace being entirely open the convenience for roasting pre-mentioned when requisite. By inserting a water vessel in a heater above the advantages of carrying off the steam & of absorbing or neutralizing the effluvia may be attained in the same manner as in the cooking stove.
